Primary Examiner — T. Chase Nelson*Assistant Examiner* — Mark Cavanna(74) *Attorney, Agent, or Firm* — Brinks Gilson & Lione(57) **CLAIM**

We claim the ornamental design for a container for analyzer, as shown and described.

DESCRIPTION

FIG. 1 is a perspective view of a container for analyzer of the present invention;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a cross-sectional view taken along the line 8 of FIG. 4; and,

FIG. 9 is a second perspective view thereof shown with the lid in an open position.

The broken lines shown represent unclaimed subject matter and form no part of the claimed design.
